U.S. Cl. D6—181

FIG. 1

FIG. 2

FIG. 3

FIG. 1 is a three-quarters perspective view of a combined electric eraser support hook and accessory holder for a draftsman showing my new design;

FIG. 2 is a cross-sectional cutaway view of my combined electric eraser support hook and accessory holder for a draftsman taken along line 2—2 shown in FIG. 1;

FIG. 3 is a rear elevational view of my new design;

FIG. 4 is a perspective view of my new design in an environmental context;

FIG. 5 is a left side sectional view of my new design;

FIG. 6 is a perspective view of the top and front of my combined electric eraser support hook and accessory holder for a draftsman showing my new design; and

FIG. 7 is a top plan view illustrating my new design.

The right side view of my new design for a combined electric eraser support hook and accessory holder for a draftsman is a mirror image of the left side view.

I claim:

The ornamental design for a combined electric eraser support hook and accessory holder for a draftsman, substantially as shown and described.
